UNITED STATES PATENT OFFICE.

HOWARD F. GURNEY, OF JERSEY CITY, NEW JERSEY.

ELECTRIC-ELEVATOR CONTROLLER.

No. 851,933.

Specification of Letters Patent.

Patented April 30, 1907.

Application filed April 30, 1906. Serial No. 314,397.

To all whom it may concern:

Be it known that I, HOWARD F. GURNEY, a citizen of the United States, and a resident of Jersey City, in the county of Hudson and State of New Jersey, United States of America, have invented certain new and useful Improvements in Electric-Elevator Controllers, of which the following is a specification.

My invention relates to an electric controller for stopping, starting and reversing an electric motor and is especially adaptable for use in connection with an electric elevator.

I will describe my invention in the following specification and point out the novel features thereof in claims.

Referring to the drawings, Figure 1 is a diagram showing certain apparatus and electrical circuits which embody my invention. Fig. 2 is a view of some of the parts shown in Fig. 1, but with the parts in another of their operative positions. Fig. 3 is a sectional elevation of a detail.

Like characters of reference designate corresponding parts in all of the figures.

25 + and - designate mains from a suitable source of electrical supply which, after passing through a main-line switch 10, pass to various parts of the apparatus through circuits which will be fully described later.

30 20 is a starting switch for the motor and it comprises a plurality of stationary contacts, here designated by 21, 22, 23, 24, 25 and 26, and two movable contacts or contact-plates 27 and 28. These movable contact-plates 35 are attached to but insulated from a vertical rod 29 which is connected by means of another rod 47 to the core 46 of a solenoid magnet, the winding of which is designated by 45.

50 57 designates an air-cushion which may be 40 interposed between the solenoid 45 and the starting switch 20, and this air-cushion may be constructed as shown of a hollow cylindrical shell closed at both ends and a piston 58 adapted to fit more or less closely within 45 this cylindrical shell. This piston 58 is attached to the rod 47.

55 50 30 designates a reversing switch somewhat similar in construction to the starting switch 20 and it comprises a plurality of stationary contacts 31, 32, 33, 34, 35, 36, 37 and 50 38 and two movable contacts or contact-plates 39 and 40 which are attached to but insulated from a vertical rod 41. This vertical rod 41 is arranged to be directly above 55 the vertical rod 29. A pendent 42 is pivoted at the lower end of the rod 41 at 43 and ar-

ranged to normally remain in alignment with the rods 41 and 29. This pendent is provided with a slot 42^a into which a pin 91^b projects. This pin 91^b is on a rod 91^a, one end of which is attached to the core 91 of a solenoid 90. A contact-plate 92 is connected to but insulated from the other end of the rod 91^a. This contact-plate is arranged to be moved against and to bridge stationary contacts 93 and 94 or stationary contacts 95 and 96. The core 91 and its connected contact-plate 92 is arranged to be normally held in one direction by a spring 98 or by other suitable means until the contact-plate 92 connects and bridges the stationary contacts 93 and 94. The core 91 is arranged to be moved in the other direction whenever the solenoid 90 is energized until contact-plate 92 bridges and connects stationary contacts 95 and 96. At the same time, this will cause the pin 91^b to be moved to one side and the pin will therefore draw the pendent 42 to one side into the position indicated by dotted lines.

50 50 designates an electric motor which is to be controlled and it comprises an armature 51 and a shunt-field 54. The armature terminals are connected by conductors 52 and 53 to stationary contacts 32 and 34, respectively. The shunt-field terminals are connected by conductors 55 and 56 to stationary contacts 25 and 24, respectively.

70 70 designates an automatic rheostat arranged to gradually cut a resistance out of the motor circuit. This rheostat comprises a movable brush 71 which is insulated from but mounted upon a rod 75. This brush 71 is arranged to bear upon a stationary contact 72 and to be moved over the contact 72 and a plurality of stationary contacts 73, 73, 95 to which contacts a resistance 74 is connected. The lower end of rod 75 extends into a dash-pot 77 and is connected to a piston 78 within the dash-pot. The piston 78 is provided with a valve 78^a which is closed upon the downward movement of the piston 78 but which is automatically opened upon the upward movement of the piston 78. The cylinder of the dash-pot 77 is preferably arranged to be filled with oil and in a well-known manner offers resistance to the quick movement of its piston 78 on its downward stroke, but offers but little resistance to the movement of its piston during its upward stroke. I prefer to construct the dash-pot 105 77 with a by-pass 79 which extends from the bottom of the cylinder of the dash-pot to a

- point somewhat below the upper end of the piston's travel. The size of this by-pass may be regulated by means of a screw 79^a. Above the automatic rheostat 70 is a movable contact 89 which is arranged to be moved up against a stationary contact 88 by the rod 75 when the latter is at the upper end of its travel. 88^a designates a resistance which is connected between the stationary contacts 88 and 89.
- 120 designates a rod which is pivoted at 121 and which is arranged to connect the rod 47, which is connected to the solenoid 46, to the rod 75 of the automatic rheostat 70.
- 15 This it does by means of a pin 122 on the rod 47 and a similar pin 123 on the rod 75. The pins are so arranged that when the starting switch 20 is open and the rods 29 and 47 are in their lowest position the pin 122 will rest upon one end of rod 120 and bear that end downward and this will at the same time cause the other end of rod 120 to be raised against the pin 123 and to thereby cause the rod 75 to be moved to its upper position.
- 20 60 designates a brake which is arranged to be actuated by the solenoid 45. This brake is arranged to act upon a brake-pulley 61^a which is preferably arranged to be connected directly to the shaft 61 of the motor 50. The
- 25 30 brake 60 comprises two brake-levers 62, 62 which are pivoted at 63, 63 and which are connected in a suitable manner to a weighted arm 64 which is pivoted at 65 and which is connected at 66 to the solenoid core 46.
- 35 Before proceeding with the description of the rest of the apparatus I will point out the operation of this brake 60. The weighted arm 64 together with the weight of the solenoid core 46 and its connected parts normally
- 40 tend to press the brake-levers 62, 62 against the brake-pulley 61^a. When, however, the solenoid coil 45 is energized and thereby raises its core 46 the weighted arm 64 is moved about its pivot in such a manner as to
- 45 remove the brake-levers 62, 62 from the brake-pulley 61^a.
- 50 80 designates an elevator-car which may be connected to the motor 50 in any suitable manner. A manually operated switch 81
- 55 may be placed in this car. This switch comprises a lever 82 which is pivoted at 83, and two stationary contacts 84 and 85, against one or the other of which the pivoted lever 82 may be moved.
- 55 83^b designates a slack cable switch of any of the well-known forms which is arranged to be opened whenever the elevator-car hoisting-cables are deranged and become slack.
- 60 100 designates an automatic stop-motion switch which may be arranged to be actuated by the motion of the elevator-car or its hoisting mechanism. It comprises two switch arms 101 and 102. These switch arms are
- 65 arranged to be actuated by a cam 105 which

is moved to actuate either the arm 101 or the arm 102 whenever the car reaches one end or the other of its travel. The switch arm 101 is arranged to control contacts 103 and the switch arm 102 is arranged to control contacts 104. These contacts are in circuits which will be presently pointed out.

I have pointed out the various parts of the apparatus which I use in carrying out my invention and I will now trace their connecting electrical circuits and describe the operation of the various parts. The main-lines + and - are connected by means of the conductors 11 and 14 to the stationary contacts 26 and 22. A conductor 83^a is connected to the positive or + main and through the slack cable switch 83^b to the pivoted arm 82 of the car-switch 81. If an operator in a car now moves the arm 82 to the right so that it comes in contact with the stationary contact 85, a circuit will be completed thereby through conductor 85^a, contact 104 of the stop-motion switch and to stationary contact 93. This is now connected by contact-plate 92 to stationary contact 94 and the circuit will continue through conductor 86 to one of the terminals of the winding of solenoid 45. The other terminal of this solenoid winding is connected by a conductor 87 to the stationary contact 88. The movable contact 89 is now in contact with stationary contact 88 and the circuit will thereby continue through these contacts and through conductor 14^a to the negative or - main, to which it is connected. A current will therefore flow through the solenoid 45 and it will be energized thereby and will raise its core 46 with its connected parts. The brake-levers will be released by this operation as has already been shown. The contact-plates 27 and 28 will be raised up so that they connect stationary contacts 21, 22, and 25, 26, respectively. The upward movement of rod 29 will push the pendent and its connected rod 41 upward until the contact-plates 39 and 40 contact with and connect stationary contacts 33, 34 and 37, 38, respectively. A projection 44 is provided upon the rod 41 and this will now be raised above and latched upon a projection 97 which is connected to solenoid core 91. The rod 41 and its connected parts will be held thereby in their raised position until further acted upon in a manner which will appear later.

When the parts are now raised into the positions above described the current will flow to the motor 50 through the following paths. The shunt-field 54 will be connected directly across the main-lines because its conductor 55 which is connected to stationary contact 25 is now connected to the positive main 11 by the contact-plate 28 which bridges contacts 25 and 26; and its conductor 56 which is connected to stationary contact 24 will now be connected to the other main by the

contact-plate 27 which bridges contacts 21 and 22, the latter of which, 22, is connected directly to the negative main 14 and the other of which, 21, is permanently connected 5 to stationary contact 24. At the same time a current will flow to the motor armature 51 from positive main 11, stationary contacts 26 and 25, which are bridged by contact-plate 28, through conductor 12, resistance 74, to the upper of stationary contacts 73; thence through brush 71, stationary contact 72, conductor 13 to stationary contact 37. This is now connected to stationary contact 38 by the contact-plate 40, and stationary 15 contact 38 is connected to one of the motor armature terminals by conductor 52. The other motor armature terminal is connected by conductor 53 to stationary contact 34 which is now connected by contact-plate 39 20 to stationary contact 33. The latter stationary contact 33 is connected by conductor 15 to stationary contact 21 which is now connected to stationary contact 22 by contact-plate 27 and the circuit is thereby completed 25 by the negative main 14. This will cause the motor to rotate in one direction and its connected car to travel in one direction. For example, the car may be moved upward.

The solenoid core 46 will, at the same time 30 that it has closed the starting switch 20 and actuated the reversing switch 30, raise pin 122 above the end of pivoted rod 120. This will cause the other end of rod 120 to be moved down below the path of travel of pin 35 123 on rod 75 and will allow the brush 71 to move down over stationary contacts 73 under the action of the dash-pot 77. This will cause the resistance 74 to be gradually cut out of the motor armature circuit and will 40 allow the motor to gradually accelerate. The dash-pot 77 is constructed, as before described, for the purpose of causing the first movement of the brush 71 across the stationary contacts 73 to be slower than the remainder of its movement. This purpose of preventing the motor from receiving too great an inrush of current and for providing means for the armature to get into motion gradually before too much of the starting 45 resistance is cut out from its circuit. The remainder of the travel of brush 71 may be regulated by means of the screw 79^a to cause the acceleration of the motor to be made at the desired rate. It may be seen by an inspection 50 of the diagram that when the brush 71 has reached the lower of contacts 73, the entire starting resistance 74 is cut out from the motor armature circuit and that the current will pass directly from the main 11 to the 55 left-hand motor armature terminal.

As soon as the upper portion of rod 79 is moved down away from contact 89 the contact 89 will drop away from the stationary contact 88 and will thereby cause the resistance 88^a to be inserted in the circuit with so-

lenoid winding 45. This serves a double function, for it reduces the amount of current which passes through solenoid 45, and thereby adds to the economy of operating this device, and at the same time the resistance 88⁷⁰ causes the resistance of the circuit of the solenoid winding 45 to be so great that the solenoid cannot be sufficiently energized to raise its core 46, if the latter is in its down position, until the contact 89 is again moved 75 against the contact 88. This will make it impossible to close the starting switch 20 until all of the resistance 74 is again inserted in the armature circuit. The motor will continue to run in this direction until the operator moves the contact-arm 82 away from stationary contact 85, or until the automatic stop-motion switch 100 breaks the contacts at 104, in either of which cases the circuit, through solenoid winding 45, will be broken 85 and the solenoid core with its connected parts will return to their original position. This will cause the contact-plates 27 and 28 to drop back away from stationary contacts 21, 22 and 25, 26, and will cause the contact-plate 28 to drop against and connect stationary contacts 23 and 24; at the same time, it will cause the brake 60 to be applied 90 and the motor will come to rest. The rod 41 of the reversing switch 30 will, however, remain in its raised position, because of the projection 44 being latched against the projection 95 97. The air-cushion 57 may be placed, as shown, to prevent the slamming of the parts actuated by solenoid core 46 in both 100 their upward and downward movements.

When the contact-plate 28 is moved down against stationary contacts 23 and 24, a circuit is completed thereby from the motor armature 51, through conductor 52, stationary contact 38, contact-plate 40 and stationary contact 37, conductor 13 to stationary contact 72; thence through brush 71 to contacts 73, and through a part of the resistance 74 and conductor 23^a to stationary contact 23; thence, through contact-plate 28 to contact 24 which is connected by conductor 15 and contact-plate 39 to the other motor armature terminal by conductor 53. This will cause the motor armature to generate by its motion 110 115 a current through a portion of resistance 74 which will put a load upon the motor and will cause the latter to come to rest more quickly.

When the starting switch 20 is closed the pin 122 will be raised somewhat above the upper end of the rod 120. This is for the purpose of allowing the contact-plates 27 and 28 to be moved away from their stationary contacts before the weight of the core 46 and its connected parts is called upon to do any additional work. A further movement, however, of the core 46 and its connected parts will cause the pin 122 to be brought down upon the right-hand end of rod 120 and will 125 130

cause the other end of rod 120 to push upward against pin 123 and to thereby raise brush 71 to its upper position. The portion of resistance 74, then, which remains in the 5 motor armature circuit while the motor is coming to rest, will be that portion which is connected between the upper stationary contact 73 and the conductor 23^A.

- If the motor has been stopped by the operator, moving pivoted arm 82 away from stationary contact 85 in the car-switch 81, the 10 motor may be started by his repeating the operation, but without any effect whatever on the reversing switch 30 which will remain 15 in its upper or raised position which is shown in Fig. 2. If, however, the operator desires to start the motor in the opposite direction, and to thereby cause the car to move downward, he will move pivoted contact arm 82 20 against stationary contact 84 in the car-switch 81. This will cause a circuit to be completed through conductors 83^A and 84^A, contact 103 of the automatic stop-motion switch and conductor 84^B to one end of solenoid winding 90. The other end of this solenoid winding is connected by a conductor 14^A 25 to the main line conductor 14. Solenoid 90 will thereby be energized and will pull its core 91 to the right. This will move contact- 30 plate 92 against stationary contacts 95 and 96, and will thereby close a circuit through solenoid winding 45 in the manner previously described. It will, at the same time, move the projection 97, which is connected to 35 solenoid core 91, away from the projection 44 on rod 41 and allow the rod 41 to drop so that its contact-plates 39 and 40 will move down onto contacts 31 and 32, and 35 and 36, respectively, and will also move the pendant 42 40 over into the position indicated by dotted lines, in which position it is out of the path of travel of the rod 29. The starting switch 20 may therefore be closed without affecting the position of the reversing switch 30. By 45 tracing the circuits it may be seen that the operation is similar to that already described, but that in this case the mains 11 and 14 are connected to the motor armature 51 in the opposite direction. The motor will therefore 50 rotate in the opposite direction and the automatic rheostat 70 will cause the motor to accelerate in the manner already described. The operator may again bring the motor to rest by moving the pivoted contact-arm 82 55 away from stationary contact 84. He may start the motor up again in the same direction and the operation will be the same as that already described, except that the reversing switch 30 will remain in its down- 60 ward position.

In the arrangement herein shown and described I have provided a starting switch and a reversing switch for an electric motor with the parts so arranged that the starting switch 65 may be actuated independently of the revers-

ing switch and so that the reversing switch will remain in the position in which it was last used so that the motor may be started and stopped any desired number of times without actuating the reversing switch, but so 70 that the reversing switch will be actuated whenever the operator desires to run the motor in the opposite direction from that last used. This is a decided improvement over devices formerly used. This controller, 75 which I prefer to call a straight-line controller, has many other advantages which may be readily seen and which will be fully pointed out in the following claims, but which are capable of modifications and are therefore 80 not limited to the exact construction and arrangement of the parts herein shown and described.

What I claim is.—

1. In combination with a motor, a reversing switch therefor having two operative positions and arranged to be held in either of said operative positions, an electrically actuated starting switch for said motor arranged to be actuated independently of the reversing switch and means for mechanically connecting the reversing switch to move with the starting switch. 85

2. In combination with a motor, a reversing switch therefor having two operative positions and arranged to be held in either of said operative positions, a starting switch for said motor, an electromagnet arranged to actuate the starting switch independently of the reversing switch, and means for mechanically connecting the reversing switch to be actuated by the electromagnet with the starting switch. 95

3. In combination with a motor, a brake, a reversing switch for the motor having two operative positions and arranged to be held in either of said operative positions, a starting switch, an electromagnet arranged to actuate the brake and the starting switch independently of the reversing switch, and means for mechanically connecting the reversing switch to be actuated by the electromagnet with the brake and the starting switch. 105

4. In combination with a motor, a brake, a starting switch for the motor, an electromagnet arranged to actuate the starting switch and the brake, and an air-cushion arranged to control the movement of the electromagnet in both directions. 115

5. In combination with a motor, circuits therefor, a brake, an automatic rheostat in the motor circuits, a reversing switch for the motor having two operative positions and arranged to be held in either of said operative positions, a starting switch, an electromagnet arranged to actuate the brake and the starting switch independently of the reversing switch and to control the automatic rheostat, and means for mechanically connecting 125 130

the reversing switch to be moved by the electromagnet with the brake and the starting switch.

6. In combination with a motor, circuits therefor, a brake, an automatic rheostat having a resistance in the motor circuit, a reversing switch for the motor having two operative positions and arranged to be held in either of said operative positions, a starting switch, an electromagnet arranged, when energized, to actuate the starting switch and the brake independently of the reversing switch and to control the automatic rheostat, means for mechanically connecting the reversing switch to be moved by the electromagnet with the starting switch and the brake, and means to prevent the energization of the electromagnet until all of the resistance of the automatic rheostat is in the motor circuit.

7. In combination with a motor, circuits therefor, a brake, an automatic rheostat having a resistance in the motor circuit, a dash-pot for controlling the action of the rheostat, said dash-pot arranged to control the rheostat to cut out a portion of the resistance from the motor circuit slowly and to cut out the remainder of the resistance more rapidly at a predetermined rate of speed, means for regulating said predetermined rate of speed, a reversing switch for the motor having two operative positions and arranged to be held in either of said operative positions, a starting switch, an electromagnet arranged, when energized, to actuate the starting switch and the brake independently of the reversing switch and to control the automatic rheostat, and means for mechanically connecting the reversing switch to be moved by the electromagnet with the starting switch and the brake.

8. In an electric elevator, the combination of a motor, an elevator-car, a reversing switch for the motor having two operative positions and arranged to be held in either of said operative positions, a starting switch for said motor, an electromagnet arranged to actuate the starting switch independently of the reversing switch, and means for mechanically connecting the reversing switch to be actuated by the electromagnet with the starting switch.

9. In an electric elevator, the combination of a motor, an elevator-car, a brake, a starting switch for the motor, an electromagnet arranged to actuate the starting switch and the brake, and an air-cushion arranged to control the movement of the electromagnet in both directions.

10. In an electric elevator, the combination of a motor, an elevator-car, circuits for the motor, a brake, an automatic rheostat in the motor circuits, a reversing switch for the motor having two operative positions, and arranged to be held in either of said operative

positions, a starting switch, an electromagnet arranged to actuate the brake and the starting switch independently of the reversing switch and to control the automatic rheostat, and means for mechanically connecting the reversing switch to be moved by the electromagnet with the brake and the starting switch.

11. In combination with a motor, circuits therefor, a brake, an automatic rheostat in the motor circuits, a dash-pot for controlling the action of the rheostat, said dash-pot arranged to control the rheostat to cut out a portion of the resistance from the motor circuits slowly and to cut out the remainder of the resistance more rapidly at a predetermined rate of speed, means for regulating said predetermined rate of speed; a reversing switch for the motor having two operative positions and arranged to be held in either of said operative positions, a starting switch, an electromagnet arranged, when energized, to actuate the starting switch and the brake independently of the reversing switch and to control the automatic rheostat, means for mechanically connecting the reversing switch to be moved by the electromagnet with the starting switch and the brake, and means to prevent the full energization of the electromagnet until all of the resistance of the automatic rheostat is in the motor circuit.

12. In combination with a motor, a reversing switch therefor, said reversing switch having a movable member arranged to be held in one operative position by gravity and in a second operative position by a latch, an electrically actuated starting switch for the motor arranged to be actuated independently of the reversing switch, means for mechanically connecting the movable member of the reversing switch to be moved by the starting switch into its second operative position, and means for releasing said latch and allowing the reversing switch to move back into its first operative position.

13. In combination with a motor, a reversing switch therefor, said reversing switch having a movable member arranged to be held in one operative position by gravity and in a second operative position by a latch, an electrically actuated starting switch for the motor arranged to be actuated independently of the reversing switch, means for mechanically connecting the reversing switch to be moved by the starting switch into its second operative position, and an electromagnet for controlling the connecting means and for releasing the latch to allow the reversing switch to move back into its first operative position.

14. In an electric elevator, the combination of a motor, an elevator-car, a reversing switch for the motor having two operative positions and arranged to be held in either of said operative positions, a starting switch for said motor, an electromagnet arranged to

actuate the starting switch independently of the reversing switch, means for mechanically connecting the reversing switch to be actuated by the electromagnet with the starting switch, and a manually operated switch in the car.

15. In an electric elevator, the combination of a motor, an elevator-car, circuits for the motor, a brake, an automatic rheostat in the motor circuits, a dash-pot for controlling the action of the rheostat, said dash-pot arranged to control the rheostat to cut out a portion of the resistance from the motor circuit slowly and to cut out the remainder of the resistance more rapidly at a predetermined rate of speed, means for regulating said predetermined rate of speed, a reversing switch for the motor having two operative positions and arranged to be held in either of said operative positions, a starting switch, an electromagnet arranged, when energized, to actuate the starting switch and the brake independently of the reversing switch, and to control the automatic rheostat, means for mechanically connecting the reversing switch to be moved by the electromagnet with the starting switch and the brake, means for preventing the full energization of the electromagnet until all of the resistance of the automatic rheostat is in the motor circuit, and a manually operated switch in the car.

16. In combination with a motor, a reversing switch therefor having two operative positions arranged to be held in either of said operative positions, a starting switch, an electromagnet arranged to actuate the starting switch independently of the reversing switch, a circuit for said electromagnet, a second electromagnet arranged to mechanically connect the reversing switch to be moved by the starting switch, said electromagnet being arranged to control the circuit of the first electromagnet.

17. In an electric elevator, the combination of a motor, an elevator-car, a reversing switch for the motor having two operative positions and arranged to be held in one of

said operative positions by gravity and in another of its operative positions by a latch, a starting switch, an electromagnet arranged to actuate the starting switch independently of the reversing switch, a circuit for said electromagnet, a second electromagnet arranged to be moved by the starting switch into its second operative position and to release the latch, and allow the reversing switch to move back into its first operative position, contacts controlled by said second electromagnet, the circuits of the first electromagnet being connected to said contacts and controlled by said second electromagnet.

18. In an electric elevator, the combination of a motor, circuits therefor, an elevator-car, a brake, an automatic rheostat in the motor circuits, a reversing switch for the motor, having two operative positions and arranged to be held in one of said operative positions by gravity and in the other of said operative positions by a latch, a starting switch, an electromagnet arranged to actuate the brake and the starting switch independently of the reversing switch, and to control the automatic rheostat, a circuit for said electromagnet, a second electromagnet arranged to mechanically connect the reversing switch to be moved by the starting switch into its second operative position and to release the latch and allow the reversing switch to move back into its first operative position, contacts controlled by said second electromagnet, a circuit of the first electromagnet being connected to said contacts and controlled by said second electromagnet, means for preventing the actuation of the first electromagnet until all of the resistance of the automatic rheostat is in the motor circuit, and a manually operated switch in the car.

In testimony whereof I have signed my name to this specification in the presence of two subscribing witnesses.

HOWARD F. GURNEY.
